OIL-PUMP.

984,811.

Specification of Letters Patent.

Patented Feb. 21, 1911.

Application filed October 4, 1909. Serial No. 520,765.

To all whom it may concern:

Be it known that we, BENGT M. W. HANSON and CARL L. GROHMAN, citizens of the United States, residing at Hartford, in the county of Hartford and State of Connecticut, have invented certain new and useful Improvements in Oil-Pumps, of which the following is a specification.

This invention relates to oil-pumps.

10 An oil pump involving our invention can be employed with advantage in many different connections and the same possesses several novel features each having utility and which can be used separately or 15 jointly.

One of the more important features of the invention is the balancing of certain parts of the pump by reason of which long life thereof is assured. Another is a casing 20 of such kind that a proper and nice fitting of gears therein can be secured.

Other advantageous points will be fully set forth in the following description where-in we outline in detail that form of embodiment which we have selected for illustration in the drawings accompanying and forming part of the present specification. We do not restrict ourselves to the disclosure made by said drawings and description for certain variations may be adopted 30 within the scope of our invention as expressed in the claims succeeding said description, the detailed showing being provided so that those skilled in the art can 35 practice the invention.

Referring to said drawings, Figure 1 is a front elevation of a pump embodying our invention. Fig. 2 is an end elevation of said pump as seen from the right in Fig. 1. 40 Fig. 3 is a cross section on the line 3—3 of Fig. 1, and, Fig. 4 is a longitudinal sectional view on an enlarged scale.

Like characters refer to like parts throughout the several figures.

45 Preferably the pump comprises two intermeshing spur gears 2 and 3 inclosed by a suitable casing such as that denoted in a general way by 4. This casing is shown as consisting of two side-plates 5 and 6 and 50 an intermediate plate or spacing member 7, the plate 6 preferably having a foot or base 8 adapted to be attached in some substantial manner as by screws 8', to the bed 9 of the machine in connection with which the pump 55 is associated. Said three plates are rigidly

connected or tied together in some convenient manner as by the screws 10 and dowels 11 arranged in alternation. The inner faces of the two side plates 5 and 6 are dressed or machined off smooth and the same applies to the opposite faces of the intermediate plate 7 to thereby insure proper and accurate fitting together of said plates. The intermediate plate 7 is shown as having two intersecting circular openings 12 and 13 the presence of which together with the adjacent surfaces of the outer plates 5 and 6, produces chambers in which the intermeshing gears 2 and 3, respectively, turn and said plate 7 also has two passages 14 and 15 preferably interiorly tapped to receive pipes (not shown). Assuming that the gears rotate in the direction of the arrows in Fig. 3 the passage 14 will constitute a supply port while the passage 15 will serve as a discharge port, the direction of flow of the oil being also indicated by arrows in said figure.

The gears 2 and 3 serve as pumping elements and their shafts are denoted respectively by 16 and 17. Each shaft is connected with its gear in such manner that the latter may have a lateral motion and the former a longitudinal motion but the motion in each case is almost imperceptible and the purpose thereof will be made evident hereinafter. Practically therefore both shafts and both gears are capable of floating.

From the two side plates 5 and 6 there are shown extending outwardly the elongated hubs or bearings 18 and 19 respectively and the shafts turn in these hubs or bearings. The shaft 16 fits somewhat freely in said hubs or bearings 18 and 19, closed by plugs 20 in a liquid-tight manner. There are spaces 16' and 16'' between the ends of said shaft 16 and the two plugs and the purpose of these spaces will be hereinafter set forth.

As a convenient means for rotatively connecting the gear 2 with its supporting shaft 16 a dowel-like key 21 may be provided, such key fitting a keyway in said gear 2 and being driven into a socket in said shaft 16. The key for connecting the gear 3 with its shaft 17 is denoted by 22. It should be stated at this point that both gears have a sliding connection with their shafts by reason of which they can move laterally with

respect to said shafts to insure a proper balance of the same irrespective of the shafts separate means being provided to balance said shafts as we will hereinafter 5 explain.

The oil is carried around by the spaces or pockets between the teeth of the two gears 2 and 3 and leading from the outer portions of said gears are ducts or channels 10 23 of which there are four there being two directly-opposite ducts or channels associated with each gear. Such ducts or channels are formed in the inner faces of the side plates 5 and 6 and their inner ends open or lead 15 into circular rabbets 23' constituting annular ducts, surrounding the two shafts and formed in the inner faces of said plates 5 and 6 around the openings therein through which said two shafts 16 and 17 extend. 20 The oil is under pressure and under normal conditions it is pressed in a thin film between the sides of two gears 2 and 3 and the contiguous faces of the side plates 5 and 6 which is possible owing to the free lateral 25 fit of the said gears of which mention has been made. Prior to the present pump the oil under pressure would press these gears sidewise and would jam them against one or the other of the side faces of their 30 casing the consequence being uneven wear thereof; in addition to this prior defect the shafts for said gears were also thrust longitudinally by the pressure which caused a like difficulty, all of which, however, we 35 eliminate in view of the fact that the gears and shafts are perfectly balanced. There may be cases where it might only be necessary to balance the gears and others where it might only be necessary to balance the 40 shafts from which it will be evident that the balancing features may be employed separately.

The key 21 is shown as having a groove 24 and the key 22 a groove 25 by reason of 45 which the opposite sides of the two gears are put into direct communication. The oil is forced out the port 15 under pressure and owing to this pressure the oil is also forced between the sides of the gears and the plates 50 5 and 6 but in view of the fact that opposite sides of said gears are in uninterrupted communication it follows that said gears are balanced on their shafts and it will be evident that the oil in the almost infinitesimal 55 spaces between the gears and said plates, lubricates the former.

There may be cases where a gear may be jammed against one side or the other of its casing independently of pressure, such as 60 from jars, and the ducts 23 to which I have referred will then carry oil sufficient to insure balance being restored. For example let us take the gear 3 and assume that from some jar the same has been forced to the 65 right in Fig. 4. In such an event the oil

will be led from the tooth spaces into the duct 23 on the left in said figure into the keyway of said gear 3, through the groove 25, again into said keyway and finally into the duct 23 on the right in said figure to 70 centralize said gear 3 or to balance the same and in view of the presence of these ducts the balance can be much more quickly restored than if they were not present. Then also the ducts insure there always being sufficient oil present to adequately lubricate both sides of the gears even though should one of them momentarily be thrust against the side of its chamber it being clear that the gears as they sweep across the said ducts 23 80 will take up oil sufficient for lubrication. Both gears therefore run practically frictionlessly and their life is materially prolonged as regards the usual gears in pumps of the present type. The oil which is under the action of the pump therefore in the present instance acts as the balancing means for the said gears and such oil also flows through the openings in the casing in which the shafts 16 and 17 turn so as to lubricate 85 the exteriors of these shafts and also of the bearings in which they turn, the oil following the shafts throughout practically their entire extent.

Both shafts 16 and 17 are balanced as 90 we will now set forth first describing the construction and mounting of the shaft 16. It will be remembered that there is an interval between each end of the shaft 16 and the adjacent plug 20 and such intervals or 100 spaces 16' and 16'' can be utilized as balancing chambers and as will be seen they are in direct communication by a bore or passage 26 extending the complete length of the shaft 16 by reason of which there is no tendency on the part of the oil under pressure which passes along the outside of said shaft 16 forcing the same either to the right or left in Fig. 4 owing to the balanced 105 construction described as the oil pressures on the opposite ends of said shaft 16 are precisely the same. There may be cases, however, in which said shaft 16 may be moved in one direction or the other by extraneous influences or by agents outside the oil pressure and in such an event said shaft 16 110 will be immediately restored to its proper or neutral position substantially midway of the two plugs 20 by the balanced pressures 115 of the oil.

The shaft 17 as will hereinafter appear 120 constitutes the driving shaft of the pump and in a prior construction with which we are familiar the oil was permitted to flow oppositely along the old type of driving shaft and it was free to escape at one end but at the other it met a stuffing box from which as will be apparent unequal pressures 125 were put on the old type of shaft the greatest naturally being from that end thereof 130

where the stuffing box was situated. We prevent unequal pressures being applied to the ends of the driving shaft 17 as we do with the shaft 16 and the two gears 2 and 3 and we will now set forth the means shown whereby said shaft 17 may be perfectly balanced.

We have shown surrounding the shaft 17 near opposite ends thereof annular chambers 10 32 and 35 and the oil flowing oppositely from the gear 3 enters these annular chambers and therefore cannot act against the ends of said shaft as the respective chambers are short of said ends. From the chamber 15 32 there is illustrated extending longitudinally of said shaft 17, a passage or duct 33 from the inner or discharge portion of which the opposite ports 34 extend and pipes (not shown) may lead from these ports 34 to 20 carry away the oil. There is shown as extending downward from the chamber 35 a port 36 which may also be connected with a discharge pipe (not shown). The oil thus led off from the shafts may following the 25 usual disposal thereof, be conducted to its initial source which is generally a tank.

Any suitable means may be provided for operating the main or driving shaft 17 of the pump. For this purpose we have shown 30 a pulley 27 which, however, to prevent belt-drag, does not apply its effect directly to the shaft 17 said pulley being rotatively supported by the outer reduced end of the hub 19. Said pulley near its rim or periphery is 35 provided with a laterally-extending stud or pin 28 fitting a notch or slot 29 in the arm 30 keyed or otherwise suitably connected to the shaft 17 and held against displacement longitudinally of said shaft 17 by a nut 31 40 on said shaft or otherwise. Said nut 31 in connection with the disk 31' fastened to the opposite end of said shaft 17 prevents undue longitudinal movement thereof.

What we claim is:

1. An oil pump comprising intermeshing 45 gears constituting pumping elements, a casting inclosing said gears, having opposite ducts leading from the tooth spaces of said gears to their central openings, shafts supporting said gears, and keys connecting the 50 respective gears with their shafts, having oil passages to permit the flow of oil from each side of each gear to the other side.

2. An oil pump comprising intermeshing 55 gears constituting pumping elements, means for lubricating the sides of the gears, shafts for supporting said gears, and keys connecting the respective gears with said shafts and having oil passages to put the sides of the gears into communication, for balancing 60 said gears.

3. An oil pump comprising intermeshing 65 gears constituting pumping elements, shafts supporting said gears, and keys connecting the respective gears with their shafts, having oil passages to permit the flow of oil from each side of each gear to the other side.

4. An oil pump comprising a pair of intermeshing gears constituting pumping elements, a shaft having a sliding connection 70 with one of said gears, balancing chambers at opposite ends of said shaft, and a bore through said shaft for putting said chambers into communication.

5. An oil pump comprising a pair of 75 intermeshing gears constituting pumping elements, a shaft for slidably supporting one of the gears, balancing chambers at opposite ends of said shaft, and a duct in the shaft for putting said chambers into communication.

In testimony whereof we affix our signatures in presence of two witnesses.
